UNITED STATES PATENT OFFICE.

FRANK KOELSCH AND JOSEPH P. KRAMER, OF SCRANTON, PENNSYLVANIA.

BUSHING-PROTECTOR FOR USE IN PITCHING LAGER-BEER KEGS.

SPECIFICATION forming part of Letters Patent No. 657,702, dated September 11, 1900.

Application filed October 4, 1899. Serial No. 732,534. (No model.)

To all whom it may concern:

Be it known that we, FRANK KOELSCH and JOSEPH P. KRAMER, citizens of the United States, and residents of Scranton, in the county 5 of Lackawanna and State of Pennsylvania, have invented certain new and useful Improvements in Bushing-Protectors for Use in Pitching Lager-Beer Kegs; and we do declare the following to be a full, clear, and exact description of the invention, such as will enable others skilled in the art to which it appertains to make and use the same, reference being had to the accompanying drawings, and to letters of reference marked thereon, which form a 15 part of this specification.

Figure 1 of the drawings is a representation of a side elevation of a barrel-bushing with our invention applied thereto, the barrel being shown in section. Fig. 2 is a central vertical section through a barrel-bushing having our invention applied thereto. Fig. 3 is a similar view showing the bushing-protector in side elevation and rocked to one side previous to its removal. Fig. 4 illustrates a form 25 of protector having a funnel-shaped extension.

This invention has relation to a protector for barrel-bushings, and especially for the bushings of lager-beer kegs while in process 30 of being pitched.

In pitching a keg upon the inside the bushing thereof when smeared with the hot pitch is expanded, and on contracting when cold becomes loose in its seat and is, moreover, 35 difficult to clean, as the pitch adheres strongly thereto.

It is the object of our invention to provide means easily applied to and removed from the bushing, whereby the bushing will be 40 kept from contact with the pitch in pitching a keg, and whereby it will not become unduly heated.

With this object in view the invention consists in the novel construction and combination of parts, all as hereinafter described, and 45 pointed out in the appended claims.

Referring to the accompanying drawings, the letter A designates the bushing of a keg, having the usual tapered orifice, and B designates our bushing-protector, also of tapered 50 form, having the flange B' at its larger ex-

tremity and which is designed to be struck into the bushing with a mallet to fit closely therein. The protector is provided about midway of its length with an external annular groove b of substantial width, which is for the purpose of making the device at that point more susceptible of expansion and contraction and to allow it to give more readily when driven into the bushing. 60

The inner end portion of the device has a taper slightly greater than the taper of the orifice of the bushing in order that the protector when in place will contact therewith at a circumferential line c' near its inner end 65 or at the inner shoulder formed by the annular groove b and at no other points. The said shoulder is rounded, as shown at c². Above said groove b the device is of a diameter a little less than the orifice of the bushing and of similar taper thereto. The device is made sufficiently long to leave a space between its flange and the bushing when struck home therein, wherein a chisel or the like may be inserted to extract same when no longer 75 required.

It will be observed that while the device is securely seated in the bushing when in place it may be rocked therein from side to side and so extracted without trouble or delay. 80

The protector may be made of brass, malleable iron, or other suitable material.

Fig. 4 shows a form of protector having a funnel-shaped extension from its outer end.

Having thus described our invention, what 85 we claim as new, and desire to secure by Letters Patent, is—

1. As a new article of manufacture, the bushing-protector adapted to fit in a bushing, and having pivotal contacting points therewith, whereby it may be rocked from side to side therein, and readily removed, substantially as specified. 90

2. The combination with a barrel-bushing, of a bushing-protector adapted to fit therein, 95 and having pivotal contacting points therewith, whereby it may be rocked from side to side therein, and readily removed, substantially as specified.

3. The combination with a barrel-bushing, 100 of a bushing-protector, having its inner end portion of greater taper than said bushing,

and of less diameter than said bushing above said inner tapered portion, substantially as specified.

4. The combination with a barrel-bushing, 5 of a bushing-protector, having the inner tapered portion of greater taper than said bushing and provided with a rounded shoulder at its inner extremity, the central annular groove and the outer end portion of less di-

ameter than the orifice of said bushing, substantially as specified.

In testimony whereof we affix our signatures in presence of two witnesses.

FRANK KOELSCH,
JOSEPH P. KRAMER.
